HAIR CURLER

Agnes Murphy, Springfield, Mass.

Application February 24, 1936, Serial No. 65,499

4 Claims. (Cl. 132—33)

The invention relates to a hair curler and more especially to an adjustable hair curler.

The primary object of the invention is the provision of a device of this character, wherein the construction thereof is such that the waves as created in the use of the same can be readily and easily varied in size and also the same permanently formed.

Another object of the invention is the provision of a device of this character, wherein strands of hair grown on the head of a person can be readily and easily curled or waved for the permanent setting thereof to form a perfect headdress and without injury to the hair and is susceptible 15 of mounting upon a heating tube of standard construction.

A further object of the invention is the provision of a device of this character, which is simple in construction, thoroughly reliable and effective 20 in its operation, readily and easily handled, assuring a marcel wave to hair and of a permanent kind, strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and 30 pointed out in the claims hereunto appended.

In the accompanying drawing:

Figure 1 is a plan view of the device constructed in accordance with the invention showing strands of hair curled thereby.

Figure 2 is an exploded plan view showing the several members of the device separated.

Figure 3 is a sectional view on the line 3—3 of Figure 1 looking in the direction of the arrows.

Figure 4 is a sectional view on the line 4—4 of Figure 2.

Figure 5 is a sectional view on the line 5—5 of Figure 2.

Figure 6 is a perspective view of one of the members of the curler.

Figure 7 is a perspective view of the other member of the curler.

Figure 8 is a side elevation of the expander for the curler.

Similar reference characters indicate corresponding parts throughout the several views in the drawing.

Referring to the drawing in detail, the curler comprises a pair of members A and B, respectively, each being in the form of a tubular section 55 10 and 10', the section 10' being of slightly less

cross sectional diameter than the section 10 so that the member A constitutes a female member while the member B is a male member for telescopic interfitting of these members.

The tubular section 10 of the member A is 5 longitudinally split at 11 for expansion and contraction, the said section being inherently springy and normally contracted. The section 10' is longitudinally split at 11' and inherently springy to accommodate an expander including a spreading wedge 12 having a tip 13 in one end thereof, the said tip being bifurcated to accommodate a cord 14 as may be tied about strands of hair 15 so that the latter can be trained in a manner presently described for the curling of the hair. 15

The section 10 constituting the member A has fitted therewith a bill hook 16 through which is engaged the strands 15 of hair initially when training the same for the curling thereof by the device. This hook 16 has its bill directed outwardly with relation to the tip 12 when the tubular section 10' is fitted within the tubular section 10 so that the strands 15 of hair can be readily engaged therein. 20

Cut and bent from the section 10 of the member A are laterally directed hook-like retaining ears 17, these being spaced from each other uniformly in the direction of the length of the said section. The cutting of the ears 17 from the section 10 provides notches 18 registering with 25 said ears at one side of the split 11 in said section while alternately located with relation to these ears 17 at the other side of the split 11 are keeper notches 19. One edge of each notch 19 has provided therein seating slots 20 and adjustably engageable in these notches are the ears 21 on the section 10' of the member B, these ears being reversely bent laterally with respect to the ears 17 and the engagement of the ears 21 in the notches 19 is effected by telescoping the section 10' of the member B in the section 10 of the member A, the ears in this instance following the split 11 in the section 10 of the member A. Then by the turning of the section 10' the ears 21 thereon will enter the notches 19 and slightly 30 shift the sections 10 and 10' relative to each other, these ears 21 engage in companion slots 20 thereby locking the said sections together. 35

The section 10' of the member B at its other end has fitted therein a turning plug 22 which 50 is formed with a threaded stem 23 adjustably engaged in the wedge 12 so that by turning the plug 22 the wedge can be drawn into the tubular section 10' and in this manner the latter when within the section 10 will simultaneously spread 55

both sections and thereby further separating the ears 17 and 21 to stretch the loop strands 15 of hair engaged with these ears as is shown in Figure 1 of the drawing and in this manner 5 effecting the permanent waving of such strands.

The ears 21 are adjustable in the notches 19 and, as has been stated, to set the same in adjusted position they can be brought into engagement in the seats 20 and under such adjustment 10 a variance can be had in the wave 24 of the strands 15 of hair when coiled in a zigzag manner back and forth over the ears 17 and 21, respectively, when the members A and B are interfitted with each other. In this fashion the 15 strands of hair can be curled in a wave form.

On removal of the wedge 12 and the plug 22 from the tubular section 16' when these members A and B are interfitted the device can be worn upon a heating tube as commonly used for hair 20 waving purposes and an accessory of permanent hair waving machines or apparatuses.

When the hair strands 15 are waved by the coiling of the same reversely over the ears 17 and 21 of the device the end portions of the 25 strands are wound tightly about the section 16 of the member A so that the wave formation in the strands can be set in the use of the device.

In the telescoping of the member A over the member B of the device the longitudinal slits in 30 the section 16 thereof will frictionally hold these members in interfitted relation to each other.

What is claimed is:

1. A device of the character described comprising interfitted slidable and rotatable members 35 of split tubular form, reversely disposed and alternately arranged hook-like ears on said members for the training of strands of hair therethrough when the said strands have been wrapped about the members at one end thereof, and an 40 expander active within the members and having a tip for the fastening of ends of the strands of hair thereto remote from the wrapped portions of said strands about the members whereby on the rotating of the members a wave-like effect 45 will be given to the strands when the hook-like ears are spread apart by rotation of the members.

2. A device of the character described comprising interfitted slidable and rotatable members 50 of split tubular form, reversely disposed and alternately arranged hook-like ears on said members for the training of strands of hair therethrough when the said strands have been wrapped about the members at one end thereof,

an expander active within the members and having a tip for the fastening of ends of the strands of hair thereto remote from the wrapped portions of said strands about the members whereby on the rotating of the members a wave-like effect will be given to the strands when the hook-like ears are spread apart by rotation of the members, and means for changing the position of the expander. 5

3. A device of the character described comprising interfitted slidable and rotatable members of split tubular form, reversely disposed and alternately arranged hook-like ears on said members for the training of strands of hair therethrough when the said strands have been 10 wrapped about the members at one end thereof, an expander active within the members and having a tip for the fastening of ends of the strands of hair thereto remote from the wrapped portions of said strands about the members whereby on 15 the rotating of the members a wave-like effect will be given to the strands when the hook-like ears are spread apart by rotation of the members, and means for changing the position of the expander, the outermost member being provided with notches for accommodating the hook-like ears on the innermost member for the locking 20 of the ears on both members in spread relation to each other. 25

4. A device of the character described comprising interfitted slidable and rotatable members of split tubular form, reversely disposed and alternately arranged hook-like ears on said members for the training of strands of hair therethrough when the said strands have been 30 wrapped about the members at one end thereof, an expander active within the members and having a tip for the fastening of ends of the strands of hair thereto remote from the wrapped portions of said strands about the members whereby on 35 the rotating of the members a wave-like effect will be given to the strands when the hook-like ears are spread apart by rotation of the members, means for changing the position of the expander, the outermost member being provided 40 with notches for accommodating the hook-like ears on the innermost member for the locking of the ears on both members in spread relation to each other, and a bill hook on the outermost member next to the tip of the expander for engaging the strands of hair when training the 45 same through the hook-like ears. 50
